UNITED STATES PATENT OFFICE.

JAMES HAROLD HASTINGS, OF GLASGOW, SCOTLAND.

DUPLICATOR AND THE LIKE.

1,174,414.

Specification of Letters Patent.

Patented Mar. 7, 1916.

Application filed February 10, 1913. Serial No. 747,436.

To all whom it may concern:

Be it known that I, JAMES HAROLD HASTINGS, a subject of the King of England, residing in Glasgow, Scotland, have invented 5 certain new and useful Improvements in Duplicators and the like, of which the following is a specification.

This invention relates to duplicators and more particularly to devices for use in connection with the feeding of printable sheets thereto.

The object of the invention is to enable such machines to produce more perfect impressions and to facilitate their use especially in respect of dealing with the sheets immediately before the actual printing operation.

According to this invention therefore a duplicator fitted with my complete mechanism includes the combination of a frame, a support, for a form of characters to be printed from, carried upon the frame, and sheet-feed devices mounted upon the frame comprising a registering member and clamp 25 for positioning a pile of sheets, a sheet feeding mechanism wherein the sheet is buckled against a movable stop which subsequently releases the said sheet into printing position, a device for placing the buckling stop in 30 operative position at will independently of the normal automatic stop-operating mechanism of the machine, an impression platen adapted to co-operate with the said form, a throw-off mechanism for the platen whereby 35 the latter may be placed in inoperative position independently of the normal automatic platen-operating mechanism of the machine, means for adjusting the impression period of the platen, and a justifier for 40 the sheets as fed. It is, however, to be understood that certain of these features may be advantageously applied individually or in other combinations than that above indicated.

45 The accompanying drawings illustrate in detail one form of duplicator embodying all the features of this invention.

Figure 1 is a front elevation; Fig. 2 is a side elevation of the machine viewed from

the right, parts being shown broken away; 50 Fig. 3 is a side elevation of the machine viewed from the left; Figs. 4 and 5 illustrate respectively a registering device for a sheet pile and an adjusting device for part of the mechanism. 55

Like letters refer to like parts throughout these drawings, and the directions of movement of certain elements of the mechanism are indicated by arrows.

The machine comprises a base A, side 60 standards or frames B, B¹, a printing drum C mounted on a shaft C¹ and rotated by a handle C² through gearing C³, C⁴. The pack of sheets is assembled on a table P, and the same are adapted to be fed between the stencil-carrying drum C and the impression roller F by a rubbing block D². The rubbing block D² is suspended and arranged to be operated in any suitable or desirable manner from a shaft D journaled in the frame of 70 the machine, and connected by a gear wheel C⁵ to be rotated from the gear wheel C³ on the actuating shaft of the machine. 65

The sheet-buckling mechanism may be thrown out of gear by means of a clutch D⁶ 75 slid along the shaft D by a small hand lever D⁷ so that a pin D⁸ engages with the crank-shaft driving gear wheel C⁹ when the lever is moved over. The buckling stop with its pertinent mechanism (both to be herein-after more fully described) is caused to so operate that the sheets spring between the impression roller F and the drum C which bears a suitable form of characters to be printed from, such as a stencil underneath 80 which an inking pad is provided in the well-known manner. The impression roller is moved to and from the drum by a cam G, G¹ acting upon a depressor rod G² through a projection G³. This rod G² is pinned to an arm F² projecting from a shaft F¹, to the other end of which is also secured a second arm F³. The arms F², F³ are loosely journaled on the shaft F¹, and are provided at their free ends with open slots in which the 85 impression roller rests. Also secured to the shaft F¹ are collars F⁴, each of which has a spring-checked adjusting screw F⁵ screwed 90

95

2

through it to coöperate with lugs F^6 which project from the arms F^2 , F^3 . By adjusting the position of the screws F^5 in or out the impression roller comes earlier or later into 5 operation as the case may be. To other arms F^{10} projecting from and rigidly connected to the impression-roller shaft are also attached one end of springs F^7 whose other ends are secured to screw-adjustments 10 F^8 whereby the pressure exerted by the impression roller may be increased or diminished at will. The period of action and timing of the impression roller can also be altered by an adjustment device applied to 15 the depressing mechanism. This feature of construction is shown particularly in Fig. 3 and comprises a cam formed in two parts G , G^1 one of which is tenoned into, and may be slid over, the other by swinging the arm G^4 . The latter is guided in a slot G^5 in one 20 of the spiders of the drum and can be clamped in any position by the screw G^6 . The paper passing from the buckling stop between the impression roller and the drum 25 is checked and justified by a justifying stop or register H which comprises a long flat bar mounted on cranks H^1 whose shafts are journaled in the end frames of the machine. The register is reciprocated by a link H^2 eccentrically pivoted at H^3 to the gear C^3 . 30 As the individual sheets are fed forward by the buckling device they are squared or justified by contact with the justifying bar, which is timed to rise into position before 35 the impression roller operates, and to fall clear in synchrony with the operative upward movement of the latter.

Guides K are mounted close to the drum beyond the justifying stop and may be adjusted 40 vertically on the frame in relation to the drum. They assist in removing the printed sheets from the platen by catching under the leading edges of the sheets as they come around, and peeling them off as it were. The linkage which drives the justifying stop also moves a counter L through 45 suitable linkage L^1 , L^2 for the purpose of indicating the number of sheets printed.

As has been stated an independent throw-off mechanism for the impression roller is 50 included in this invention. Pivoted to the side frame of the machine is a small hand lever M upon one end of which is provided a handle M^1 for raising the lever, and a key 55 M^2 for depressing it. The other end M^3 of the lever M is notched at M^4 so as to receive a pin M^5 projecting from a bell crank lever M^6 under pressure from a spring M^7 . The bell crank lever is slotted at M^8 to receive 60 a guiding screw M^9 . Projecting from the lever M is another arm M^{10} which is connected by a link M^{11} to a second lever M^{12} pivoted at M^{13} . This lever at one end M^{14} takes the form of a box-cam so shaped as 65 in one position to act upon a pin G^8 pro-

jecting from the depressor rod G^2 , when the lever M is moved upward, maintaining the latter and hence the impression roller in a depressed position. When the lever M is down (as in Fig. 3) the depressor rod may 70 reciprocate quite freely in performing its normal functions in regard to the impression roller. The spring which acts to draw up the impression roller also keeps the cam M^{14} up to its work. Such a throw-off mechanism is of use for instance at starting the machine, when, say, a new stencil has been 75 put on the drum. If the impression roller is not then clear or has had no paper fed between it and the stencil the latter is damaged. The throw-off mechanism is used to 80 prevent such mishaps.

The sheet-buckling stop E is secured upon a spindle E^{15} journaled in the end frames and cranked as at E^1 . Mounted upon the 85 crank-shaft D is a cam D^9 which upon rotation acts upon the bowl E^3 and pushes up the rod E^2 against the action of the spring E^8 . Cam D^9 is so shaped as to permit the 90 rod E^2 to fall rapidly under tension of the spring E^8 , so giving a "quick return" action to the stop E . The rod E^2 is jointed at E^{17} to an oscillatory bar E^4 pivoted to the frame at E^5 and openly slotted at one end to receive the crankpin of the crank E^1 . The 95 rod E^2 is also provided with a slot E^6 to form a guide with the screw E^7 for the movements of the rod. From this mechanism the bar E^4 is oscillated up and down, 100 so causing the crank E^1 and hence the buckling stop to oscillates. One end of the shaft of the sheet buckling stop bears a cam E^9 . Adjacent to this cam is a bar E^{10} 105 which may be slid forward by a finger key E^{11} and is drawn back to the inoperative position by a spring E^{12} . The end of the bar is formed with a nose or cam E^{13} which engages the cam E^9 and causes it to turn thus placing the buckling stop E into the 110 operative or sheet buckling position quite independently of the normal working of the machine itself. It should also be noted that the buckling stop is formed in one piece and is substantially concentric with its spindle E^{15} . It presents an abutment as at E^{13} 115 against which the sheets are buckled by the forward movement of the rubbing block D^2 , while at the same time the back of the stop E^{14} subsequently presented to the sheet— 120 as the abutment recedes that is to say—is so shaped and disposed that the sheets are smoothly guided in their movement toward the sheet justifier or register H when the stop is turned to release them.

Fig. 5 illustrates in perspective an ad- 125 justable sheet-pile register which may be detachable or not from the feed-board P (see Fig. 2) or other part of the machine proper. This register comprises a blade N against the flat face of which the sheets are 130

abutted to position them, and a projecting arm N^1 provided with a slot N^7 to allow movement over and to receive a holding-down screw N^2 by which the arm may be fixed in place. A clamp N^3 is pivotally mounted upon the blade for clamping the pile of sheets under pressure of torsion springs N^4 which are not too strong to prevent the sheets being fed. A trigger N^5 , 10 conveniently pivoted on the arm N^1 engages the clamp when the latter is inoperative and may release it by simple movement of the hook N^6 when it is desired to hold the sheets, as will be clear from the drawing.

What I claim as my invention and desire to secure by Letters Patent is:—

1. In a duplicating machine, the combination of a frame, a stencil-carrying support mounted in said frame, sheet feeding devices mounted upon said frame and including an impression roller adapted to move toward and from said stencil-carrying support, supporting means for said impression roller, a reciprocating rod connected to said supporting means to actuate said impression roller, a projection on said rod, a cam engaging said projection, a pivoted key mounted on said framework and connected to control 25 said cam, and a dog associated with said pivoted key for temporarily locking the same in raised or depressed position, whereby said cam may be operated and maintained in position to place the impression 30 roller in inoperative position independently of the normal impression roller operating mechanism, substantially as described.

2. In a duplicating machine, the combination of a frame, a stencil-carrying member mounted in said frame, means for operating said stencil-carrying member, an impression roller, means for supporting said impression roller to move into and out of engagement with said stencil-carrying member, a reciprocating rod connected to said supporting means to actuate said impression roller, a projection on said rod, a cam coöperating with said projection to normally permit free operation of the impression 45 roller and arranged to be moved to confine the impression roller in inoperative position out of engagement with the stencil-carrying member, a pivoted key mounted in said frame, a link connecting said key and cam, and a dog for maintaining said key in elevated or depressed position, substantially as described.

3. In a duplicating machine, the combination of a frame, a stencil-carrying drum journaled in said frame, means for rotating said drum, a cross shaft loosely journaled in said frame, a pair of arms loosely mounted on said cross shaft, angularly projecting lugs on said arms, an impression roller 60 mounted on the free ends of said arms ad-

jacent said drum, a second pair of arms rigidly mounted on said cross shaft, collars secured to said cross shaft, angularly disposed lugs on said collars coöperating with said arm lugs, means for adjusting said lugs 70 relatively to each other to regulate the degree of impression of said impression roller, a spring interposed between said shaft arms and said frame tending to move said impression roller into engagement with said 75 drum, a reciprocating rod connected to said impression roller arms, means for operating said rod coincident with the rotation of said drum, a projection on said rod, a cam for engaging said projection to hold the rod in 80 depressed position with the impression roller out of engagement with said drum, a pivoted key provided with notches, a connection between said key and cam for actuating the latter, and a spring pressed dog 85 engaging with the notches in said key to hold the same in elevated or depressed position, substantially as described.

4. In a duplicating machine, the combination of a frame; a rotatable printing 90 drum supported upon the frame; sheet feeding devices mounted upon said frame and including an impression roller adapted to move toward and from said printing drum; a cam rod and spring for so moving 95 said roller from and toward said printing drum; a pin on the said rod; a pivoted box-cam embracing said pin; a pivoted finger key; an arm projecting from said box-cam operatively connected to said finger key; 100 notches in a part of said finger key which are concentric with its pivot; and a spring-pressed dog adapted to enter the said notches for the purpose of temporarily locking the described mechanism in place, 105 whereby the impression roller may be placed in inoperative position independently of the normal impression roller operating mechanism of the machine.

5. In a duplicating machine, the combination of a frame; a rotatable printing drum mounted therein; a gear wheel connected with said drum; a driving gear wheel meshing with said drum gear wheel; an impression roller supported to move into and out 110 of coöoperative relation with said drum; a reciprocating rod operatively connected with said roller support; a projection on said rod; a cam rotatably mounted relatively to the axis of said drum and rotatable 115 therewith, said cam being adapted to engage said projection and reciprocate said roller away from said drum; spring connections between said roller support and said frame tending to draw said roller toward said 120 drum; a justifying member pivotally mounted on one side of said impression roller; and a link connected at one end to said justifying member and at its other end eccentrically connected to said driving gear 125 130

wheel, whereby said justifying member is brought into engagement with an advancing sheet to be printed on and aline same in proper position between said drum and impression roller immediately prior to the engagement of said sheet by said impression roller.

In testimony whereof I have signed my name to this specification in the presence of two subscribing witnesses.

JAMES HAROLD HASTINGS.
